[57] **CLAIM**

The ornamental design for an oil dispenser cap shaped as an oil filter, as shown and described.

DESCRIPTION

FIG. 1 is a view of the front face of the oil dispenser cap shaped as an oil filter

Views of the rear, left and right faces of the oil dispenser cap shaped as an oil filter look identical to that shown in FIG. 1.

FIG. 2 is a view of the top face of the oil dispenser cap shaped as an oil filter

FIG. 3 is a view of the bottom face of the oil dispenser cap shaped as an oil filter

FIG. 4 is an isometric view of the oil dispenser cap shaped as an oil filter; and,

FIG. 5 is an isometric view of the oil dispenser cap shaped as an oil filter placed on the oil dispenser, which not being a part of the claimed design, is shown in broken lines to represent the environment in which the invention is used.
